UNITED STATES PATENT OFFICE.

HENRY R. STEVENS AND ROBERT L. ROCKWELL, OF SEATTLE, WASHINGTON,
ASSIGNORS, BY MESNE ASSIGNMENTS, TO ERNEST G. HOWE, TRUSTEE, OF
SEATTLE, WASHINGTON.

COMBINATION AIR-VALVE AND ELECTRIC SWITCH.

Application filed June 12, 1918. Serial No. 239,676.

To all whom it may concern:

Be it known that we, HENRY R. STEVENS and ROBERT L. ROCKWELL, citizens of the United States, residing at Seattle, in the 5 county of King and State of Washington, have invented a new and useful Improvement in Combination Air-Valve and Electric Switches, of which the following is a specification.

- 10 This invention relates to new and useful improvements in combination air valve and electric switches required to form an automatic system for bringing to a stop cars or trains operating on a mono-rail, elevated 15 or other railway system, in case the engineer, for any reason, attempts to pass a semaphore station indicating danger. It is intended that this combination shall operate in conjunction with the automatic semaphore signal system forming the subject of a 20 co-pending application of even date, Serial No. 239,677.

The object of this improvement is to provide a combination air valve and electric 25 switch arranged to be operated by so-called automatic stop levers actuated by the operating mechanism of the various semaphores of an automatic signal system for controlling the movement of cars or trains, said air 30 valve and electric switch forming the basis of a combination, the object of which is to automatically bring to a stop all such cars or trains that for any reason attempt to pass a semaphore station of the signal system 35 indicating danger.

A further object resides in the provision of an automatic car stop equipment designed to employ electromagnetic, as well as air brakes to effect the automatic stopping of said cars.

A final object is to provide a means incorporated in said automatic car stop equipment for re-setting the combination air-valve and electric switch, (the operation of 45 which effects the stoppage of the car or train) by means of an electromagnet that may be energized by closing a switch at the motorman's station.

The invention consists in the novel construction, adaptation and combination of 50 parts as will be more fully described in the following specification, illustrated in the ac-

companying drawings and finally pointed out in the appended claims.

In the drawings, Figure 1 is an end view 55 of the car truck and rail showing the arrangement of automatic stop levers and combination air valve electric switch applied to a mono-rail elevated railway system. 60

Fig. 2 is a side view of the truck and rail with combination air valve and electric switch and automatic stop levers mounted thereon to further illustrate the arrangement of these elements of the automatic 65 stop equipment.

Fig. 3 is a plan view of the valve-switch with cover 15 removed.

Fig. 4 is a longitudinal section through the stationary members of the valve-switch 70 disclosing the moving parts to view.

Fig. 5 is a top view showing the arrangement of contact fingers and contact disks of the electric switch.

Fig. 6 is a bottom view of the moving 75 element of the air valve showing the openings through it.

Figs. 7 and 8 show the details of construction of the automatic stop levers and the method used to support and operate them. 80

Fig. 9 is a diagram of the apparatus, piping and electric circuits comprising the complete automatic car stop equipment.

Fig. 10 is a top view of truck 91 showing more clearly the arrangement of levers 83 85 and 84 actuating rods 86 and 87 of the air brake equipment.

Referring more particularly to the drawings, in which similar numerals refer to similar parts throughout the several views, the automatic emergency stop equipment shown in diagram in Fig. 9 consists essentially of a suitable system of air brakes, circuit breaker trip solenoid, electromagnet brake, electric circuits for conveying 90 current to and from the several devices to be operated electrically, and an electrically re-set combination air-valve and electric switch to control the flow of air and electric current under emergency conditions. It 95 is thus seen that the combination air-valve and electric switch and the automatic stop levers required to operate it are inseparable parts of this automatic car stop equipment.

100

The air brake equipment shown in diagram in Fig. 9 is intended to represent the well known emergency straight-air brake system, the component parts being briefly 5 designated by the numeral 76 which represents the motor driven air compressor, 77 the pressure governed electric switch, 53 the compressed air reservoir, 78 a safety valve, 79 an air pressure gauge, 74 the motorman's 10 air valve, 57 the train line, 50 the reservoir line, 54 the emergency valve, which normally connects brake cylinder 56 with train line 57, thus allowing the equipment to operate as a straight-air brake system, 79' a muffler 15 attached to the end of exhaust pipe 80 connected to valve 74. 81, 82, 83 and 84 are levers, and 85, 86 and 87 are rods used to connect air cylinder 56 with the brake shoes 85'. 88 are rods used to suspend brake 20 shoes 85' in correct alignment with drive wheels 89.

Referring to Figs. 1 and 2, the numerals 1 and 1' are automatic stop levers supported near the ends of horizontally arranged channel irons 6 and 6'. These channel irons are 25 supported by means of an angle iron frame braced, riveted and bolted to form a suitable, rigid, simple and reliable support for these levers. It is intended that these frames be 30 bolted to the under side of the track rail as indicated. At the points where frames 7 and 7' are bolted to the horizontal channel irons 6 and 6', spacers 40 are provided to keep the channel irons a sufficient distance 35 apart to accommodate stop levers 1 and 1' which operate freely about accurately machined and fitted spacer sleeves 35 of Fig. 7, held in place by bolts 34 and 34'. Additional spacers 41 and 41', Fig. 2, are provided 40 between channel irons 6 and 6' and angle irons 7 and 7' to insure rigidity of construction. Bolts 42 pass through angles 7 and 7', channels 6 and 6', and spacers 40, 41 and 41', all of which are suitably punched or drilled to receive them. 45

For all practical purposes only one valve-switch per car or train is required and such valve-switch may be mounted on either side of the truck. This is made possible by providing two stop levers 1 and 1' as shown in 50 Fig. 1, so that in case a car for any reason may be turned around relative to the track, the emergency stop equipment is still effective. The "clear" positions of the levers are indicated by the dotted lines 43 and 43' in 55 Fig. 1.

The positions of levers 1 and 1' are controlled by the semaphore operating mechanism through a system of rods, bell cranks 60 and levers, as shown diagrammatically in the drawings relating to the co-pending application on the signal system of even date. It is intended that rod 4 shall represent one of the elements used to make the necessary mechanical connection between the sema-

phore operating mechanism and lever 3 carried at its pivotal point by bearing 5 mounted on the under side of channel irons 6 and 6'. Rods 2 and 2' connect levers 1 and 1' with lever 3. 70

The arrangement must be such that when the mechanism of the semaphore moves the semaphore arm to the danger position, levers 1 and 1' will be in the positions indicated in Fig. 1. When so placed, it is evident that one or the other will engage lever 10 of the valve switch in case the car should proceed past the semaphore station. This would result in a deflection of lever 10 45° to the right or left, depending upon the direction of motion of the car. 75

Reference to Fig. 4 will show that as lever 10 is moved—say, to the right—corresponding to a movement of the car shown in Fig. 2 from right to left—the curved projection 23 made integral with valve stem 11' of valve 11 will force vertically upward the movable element consisting of a ball 22, ball socket and cover 21' at the extremity of rod 21, core 20 and contact disks 17 and 17'. 80 These disks 17 and 17' will make contact respectively with contact fingers 16 and 16', thus closing two electric circuits. The first of these is from wire 59 on the motor side of the main circuit breaker 60 through solenoid 61, wire 62, contact fingers 16, disk 17 and wire 63 to the frame of the car, and from thence to the rails through which the current returns to the source. The second is from wire 64 connected directly to the 85 trolley, or contact shoe, if a third rail system is used, through wire 65, electromagnet brake 66, wire 67, contact fingers 16', contact disk 17' and wire 63 to the frame of the car, thence to the rails and back to the 90 source of supply. The first circuit allows current to energize coil 61, which raises the iron plunger 61', which in turn trips circuit breaker 60, thus turning off current to the 95 motors used to drive the car. The second 100 circuit energizes the electromagnet brake 66 which operates in conjunction with, or in 105 addition to, the air brakes. 110

By the movement of lever 10 cited, air valve 11 allows the compressed air stored 115 in reservoir line 50 to escape to the atmosphere through pipe 51, flexible hose connection 27, pipe 26, pipe 26', flexible hose connection 27' and pressure regulating valve 52. The compressed air in tank 53, connected to the emergency valve 54, by means of piping 55 forces downward the moving element 54' of emergency valve thereby compressing spring 54'' and connecting air reservoir 53 with brake cylinder 56 through 120 pipe 55 and emergency valve 54.

The amount of opening thus provided by emergency valve 54, is, to a certain extent, inversely proportional to the pressure in reservoir line 50. Hence if pressure regulat- 125 130

ing valve 52 has been previously set correctly, the pressure in reservoir line 50 will decrease to that value at which air will flow into brake cylinder 56 at such a rate as to best effect the stoppage of the car or train by means of the air brake equipment. Pressure regulating valve 52 is essentially a so-called safety valve provided with a suitable means for obtaining a fine adjustment of the pressure at which it will allow air to escape through it to the atmosphere. It is intended that this setting of air and electromagnet brakes shall afford quick, but not violent, stoppage of the car.

Before the car can proceed, it is necessary that the air valve of the valve-switch be closed and the connections between contact fingers 16 and 16' and contact disks 17 and 17' be broken. This is accomplished by energizing the iron-clad electromagnet mounted directly over the valve housing and attached thereto by means of countersunk screws 32. This is effected by means of a third electric circuit from wire 64 through wire 68, switch 69, wire 70, terminal wire 33, electromagnet 29, terminal wire 33' and wire 71 to the frame of the car, thence back to the source of supply. When electromagnet 29 is energized, armature 20 is drawn downward and the force thus exerted by it through stem 21 and ball 22 on projection 23 will be sufficient to return the moving element of the air valve, to its original position with handle 10 extending vertically downward, open the electric switch controlling current flow to the electromagnet brake 66 and the circuit breaker trip coil 61. The valve-switch re-setting circuit is complete only while switch 69 is closed, it being held normally opened by means of spring 69'. After opening switch 72 and re-setting valve 11 by momentarily closing switch 69, the motorman (with controller handle placed in the "off" position) can then re-set circuit breaker 60. He may then release the air brakes by moving handle 73 of his air valve 74 to the emergency release position, and may then proceed on his way as soon as the semaphore indicates "clear."

In the emergency release position, valve 74 connects reservoir line 50 through pipes 75 and 76 to the main air reservoir 53, thus restoring pressure in reservoir line 50, which pressure in connection with the force due to compressed spring 54" forces the moving element 54' of emergency valve 54 to such a position that brake cylinder 56 is again connected to train line 57 through pipes 55 and 58 as shown in the diagram, Fig. 9. This again allows the air brake equipment to be operated by means of motorman's valve 74 as a straight-air brake system.

It is intended that valve 11 and the combination valve-seat and base-frame 12 be made preferably of brass, also stem 21 and

tubing 31 which acts as a guide for the wrought-iron core 20 and at the same time supports the winding of the electromagnet. End pieces 28 and 30 of the electromagnet are made preferably of wrought-iron, also 70 the cylindrical cover 29. It will be seen that this construction forms a closed magnetic circuit through movable core 20, air gap 45, end piece 30, sleeve 29, end piece 28 and the small magnetic air gap between end piece 75 28 and movable core 20, due to the brass tube 31. This construction allows the design of a comparatively powerful electromagnet of small dimensions.

Disks 17 and 17' are to be made preferably of brass, also contact fingers 16 and 16'. It may be advantageous, however, to make the cylindrical contact pieces mounted at the extremities of these fingers of carbon, thus insuring freedom from the sticking together of the contact fingers and disks which may have to carry currents of considerable magnitude. Operating lever 10 may be constructed of mild steel in order to insure such lever having sufficient strength to withstand the severe strains imposed upon it when engaged by the trip levers while the car is moving at a high rate of speed. It is preferable that the valve 11 and valve stem 11' be made from the same piece of brass 95 with projections 23 and 23' formed integral therewith. In order to insure valve 11 being held firmly in connection with the valve seat 12, spring washer 13 in connection with plain washer 13' and screw 14 are used as 100 shown in Fig. 4. Cover 15, also of brass, is used to support the lever end of the valve stem and protect the working mechanism from dust and moisture.

In Fig. 3, 26 and 26' indicate air pipes attached to the valve by means of unions 36 and 36'. This construction allows the valve-switch to be readily removed from its place on the car truck for inspection, repairs or replacement. Pieces of the hose 27 and 27', 105 shown in Figs. 2 and 9, provide the necessary flexible connections between the piping on the truck and the car. The dotted lines indicated by 39 and 38', Fig. 3, represent the ports which allow the compressed air to flow from pipe 26 and 26' when the valve is turned in either one of the operative positions. With handle 10 in the position indicated in Fig. 3, it is evident that holes 110 38 and 38' through the valve, as shown in Fig. 6, will not allow air to flow from pipe 26 to 26', but if the handle be deflected 45° to the right or left, one or the other of these holes will make the necessary connection between ports 39 and 39'. The length and 115 shape of projections 23 and 23', of Fig. 3, are such that they serve in conjunction with stem 21 and its attachment to form a stop for the valve at either one of these positions. In addition, two stops 40 are provided on 120

125

130

cover 15 to limit the deflection of lever 10 from the vertical position. If for any reason the deflection of handle 10 differs slightly from the necessary 45°, the enlargements of 5 ports 39 and 39' in the valve seat and of holes 38 and 38' in the valve serve to insure the necessary area for passage of the air.

A pad of insulating material 18, Figs. 3 and 4, is used to insulate contact fingers 16 10 and 16' from the base frame 12. These fingers are shown attached to the insulating material by means of combined fastening screws and terminals 19 and 19'. The winding of the electromagnet coil 44 composed of 15 a suitable number of turns of insulated copper wire, is covered with additional insulation to adequately insulate it from the metal frame of the magnet. 33 and 33', Fig. 3, indicate the insulated flexible terminal 20 wires connected to the ends of the magnet winding and well insulated from end pieces 28 and 30 through which they pass. Disks 17 and 17' are each insulated from rod 46 by means of an insulating sleeve (not shown) 25 of suitable thickness and equal length to the thickness of the disk, also by disks of insulating material 49 placed one on each side of each disk. Washers 48 are used to protect the insulation from abrasion as nuts 30 47 are screwed into place.

The cylindrical construction of the moving part of the electromagnet and the attachments thereto make possible the use of 35 contact disks 17 and 17' of the form shown. This arrangement provides on the contact disks a multiplicity of contact points with the contact fingers 16 and 16', thus distributing the wear over a considerable area of contact surface instead of concentrating it at 40 one point as would be necessary in case the moving part of the electromagnet was not free to rotate about its axis and made integral with base frame 12 are legs 12' means of which the valve-switch is attached to the 45 frame of the truck 9 as shown in Figs. 1 and 2.

What we claim as new, and desire to protect by Letters Patent, is:—

1. A train stop mechanism for a railway 50 car in combination with the stop lever of an automatic semaphore signal system disposed at selected points along the track, a valve-switch adapted to be secured to said car comprising a lever operable by said stop lever, a member and an air valve operable by said switch lever whereby the operation of said member will close an electric circuit and effect the turning off of current from the motors that drive said car and whereby 55 the operation of said air valve will actuate the emergency valve of said car's air brake equipment whereupon said air brakes will be applied to the wheels to stop said train.

2. A train stop mechanism for a railway 60 car in combination with the stop lever of an

automatic semaphore signal system disposed at selected points along the track, a valve-switch adapted to be secured to said car comprising a lever operable by said stop lever, a member and an air valve operable by said switch lever, said member comprising contact disks adapted to close an electric circuit, a solenoid energized by the closing of said circuit, a circuit breaker actuated by the energizing of said solenoid whereby current 70 is turned off from the motors that drive said car, an emergency valve and air reservoir, and means whereby the opening of said air valve by the actuation of said switch will effect the opening of said emergency valve 75 whereupon said air brakes will be applied to the wheels to stop said train.

3. A train stop mechanism for a railway car in combination with the stop lever of an automatic semaphore signal system disposed 80 at selected points along the track, a valve-switch operatively secured to said car comprising a lever adapted to be actuated by said stop lever, a contact disk member and an air valve operable by said lever, said disk member adapted to close an electric circuit and actuate a circuit breaker thereby turning current off from the motors that drive 85 said car and means for connecting the air equipment of said car with the brake cylinders thereof by the opening of said air valve 90 whereby air brakes will be applied to the wheels to stop said train.

4. A train stop mechanism for railway 100 cars in combination with the stop lever of an automatic semaphore signal system disposed at selected points along the track, a switch operatively secured to said car comprising a lever operable by contact with said stop lever, a member comprising a plurality of contact disks actuated by said lever, said disk adapted to close two electric circuits, one of said circuits adapted to effect the turning off of current from the motors that drive said car, the other of said circuits 105 adapted to energize an electromagnet brake provided to engage said rail and stop said car.

5. A train stop mechanism for a railway 110 car in combination with the stop lever of an automatic semaphore signal system disposed at selected points along the track, a valve-switch secured to the truck of said car comprising a lever adapted to be actuated by contact with said stop lever, an air valve 115 and a member comprising a plurality of contact segment disks operable collectively by said lever, said disks adapted to close two electric circuits, one of said circuits adapted to effect the turning off of current from the motors that drive said car, the other of said circuits adapted to energize electromagnet brakes provided to engage said rail and stop 120 said car, and whereby the operation of said air valve will actuate the emergency valve 125 130

of said car's air brake equipment whereupon air brakes will be applied to the wheels to stop said train.

6. A train stop and starting mechanism for a railway car in combination with the stop lever of an automatic semaphore signal system disposed at selected points along the track, a valve-switch adapted to be secured to the frame of said car, a lever adapted to 5 be actuated by contact with said stop lever, an air valve opened and a plurality of electric circuits closed thereby whereupon current will be turned off from the motors that

drive said car and an electromagnet brake and air brakes respectively applied to stop 15 said car, and manual means for closing a circuit to actuate electromagnet means for closing said air valve and opening the electric switch preparatory to starting said car.

Signed by us at Seattle, Washington, this 20 29th day of May, 1918.
